UNITED STATES PATENT OFFICE.

EDWARD PETER JONES, OF ELLESMORE PORT, AND JOHN HARRY MIDDLETON, OF HELSBY, ENGLAND.

GRAB FOR LIFTING OR HOISTING.

Application filed June 23, 1926, Serial No. 118,082, and in Great Britain June 29, 1926.

This invention relates to grabs with mechanically operated arms for lifting and hoisting, more particularly applicable for use with overhead travelling cranes.

5 The apparatus comprises a frame suspended by three, four or more ropes and raised and lowered from two drums or winches in the overhead crane, mechanically actuated grab arms to take hold of the load which it is desired to raise or lower, and electric motor and screw or other mechanism to operate the arms or tongs to take hold of or release the load.

10 The invention will be fully described with reference to the accompanying drawings.

Fig. 1 is a side elevation partly in section of grab suspended by four ropes.

Fig. 2 is an end elevation of same.

Fig. 3 is a plan.

20 According to the invention the grab frame A which is built up of girders or bars *a* of channel, angle or other cross section is suspended at three, four or more points *b* by a corresponding number of ropes B from one, two or more winding or lifting barrels 25 of an overhead travelling crane.

It is preferred to suspend the grab frame A by four ropes B from two barrels on the overhead crane. Three suspension ropes 30 might do but it is considered that four are better and give better balance.

The grab frame A on which the grabs C are mounted is built up of suitable girders or bars *a* of suitable cross section and the tongs 35 or grabs C may take any convenient form according to the nature of the load to be lifted and sustained and they may be operated in a variety of ways.

To the upper side of the frame A at each 40 of the four corners a swivelling shackle or eyebolt D is affixed to which the four suspension ropes or chains B are attached, by which it is suspended from the crane or other lifting apparatus.

45 The frame A carries two shafts E one at either side upon which two or more grab arms C are mounted and operated by any convenient mechanical mechanism.

In the construction shown the grab arms 50 C are operated by an electric motor F through a rotary screw G driven by the

gears *g* and a nut H to which toggle levers H' are connected. The end *h* of the link or lever H' is forked and pivoted to the guide arm or lever h² and the pair of links h' are pivoted on the guide arm h² and to the grab arm C the guide arms h² being connected together by a slotted link H². The lowering or raising of the nut H draws the grab arms C together or forces them apart. In addition to the grab arms C, a swivel hook K may be fitted to the frame A.

What we claim as our invention and desire to protect by Letters Patent is:—

1. A grab for hoisting or lifting, comprising a frame, a plurality of ropes by which the frame is suspended, shackles attaching the ropes to the frame, a plurality of mechanically operated grab arms pivoted on the frame, shafts journaled in the frame on which the grab arms are mounted, a vertical rotary screw mounted in the frame, a nut on the screw and lugs on the nut, links to connect the nut with a plurality of guide arms one for each grab arm 75 journaled in the frame, shafts on which the guide arms are mounted said shafts being arranged parallel to the grab arm pivots, a slotted guide rod extending transversely of the grab at each end thereof to connect 80 opposite guide arms, a pair of links connecting each guide arm with its grab arm, a plurality of connecting rods one for each guide arm pivotally connecting it to a lug on the nut, and an electric motor and gears 85 by which the screw is rotated to operate the arms.

2. A grab for hoisting or lifting, comprising a frame, a plurality of ropes by which the frame is suspended, shackles attaching 90 the ropes to the frame, a plurality of mechanically operated grab arms pivoted on the frame, shafts journaled in the frame on which the grab arms are mounted, a vertical rotary screw mounted in the frame, a nut on the screw and lugs on the nut, a plurality of guide arms one for each grab arm 95 journaled in the frame, shafts on which the guide arms are mounted said shafts being arranged parallel to the grab arm pivots, a slotted guide rod extending transversely of the grab at each end thereof to connect 100 opposite guide arms, a pair of links connecting each guide arm with its grab arm, a plurality of connecting rods one for each guide arm pivotally connecting it to a lug on the nut, and an electric motor and gears by which the screw is rotated to operate the arms.

posite guide arms, a pair of links connecting each guide arm with its grab arm, a plurality of connecting rods one for each guide arm pivotally connecting it to a lug on the 5 nut, means for adjusting the length of the connecting rods to vary the reach of the grab arms and an electric motor and gears by which the screw is rotated to operate the arms. In testimony whereof we have hereunto set 10 our hands.

E. PETER JONES.
J. H. MIDDLETON.
